UNITED STATES PATENT OFFICE.

THOMAS C. ROBINSON, OF BOSTON, MASSACHUSETTS, ASSIGNOR OF FIVE-EIGHTHS TO E. B. WELCH AND ARTHUR E. DENISON, OF CAMBRIDGE, MASSACHUSETTS.

TACK-DRIVING MACHINE.

SPECIFICATION forming part of Letters Patent No. 594,905, dated December 7, 1897.

Application filed January 13, 1896. Serial No. 575,199. (No model.)

To all whom it may concern:

Be it known that I, THOMAS C. ROBINSON, of Boston, in the county of Suffolk and State of Massachusetts, have invented certain new and useful Improvements in Tack-Driving Machines, of which the following is a specification.

This invention relates to a tack-driving machine of the type shown in my Letters Patent No. 566,537, granted to me on the 25th day of August, 1896, said machine comprising a flexibly-supported casing or holder, a tack-delivering throat at one end of said casing, means supported by the casing for delivering tacks to the throat, a driver movable in said throat, an electric motor within the casing organized to project and retract the driver, a hand-operated motor-controlling switch on the casing, and electrical connections between said switch and motor whereby the motor is caused to project or retract the driver. Said machine also comprises tack-let-off mechanism and work-controlling pincers connected with the casing, so that the operator can last the upper and secure it during the lasting operation by tacks driven by the said driver.

The present invention has for its object to improve the construction of a machine of the character set forth in my previous application in such manner as to render its operation more satisfactory in certain particulars hereinafter pointed out.

The invention consists in the improvements which I will now proceed to describe and claim.

Of the accompanying drawings, forming a part of this specification, Figure 1 represents a side elevation of my improved tack-driving machine. Fig. 2 represents a section on line 2 2 of Fig. 1. Fig. 3 represents a section on line 3 3 of Fig. 2. Fig. 4 represents a section on line 4 4 of Fig. 1. Fig. 5 represents a section on line 5 5 of Fig. 4. Figs. 6 and 7 are views similar to Fig. 5. Fig. 8 represents a perspective view of a portion of the tack-let-off mechanism. Fig. 9 represents a partial side elevation and partial section of the machine. Fig. 10 represents a section on line 10 10, Fig. 9. Fig. 11 represents a section on line 11 11, Fig. 6. Fig. 12 represents a side view of the

preferred construction of pincers. Fig. 13 represents a side elevation showing the machine supported by a circular track. Fig. 14 represents an elevation taken from a different point, parts being in section. Fig. 15 represents a section on line 15 15, Fig. 13.

The same letters and numerals of reference indicate the same parts in all the figures.

In the drawings, *a* represents a tubular casing, which is made of iron and of such form that it can be readily grasped in the hand. The casing is preferably suspended from a support overhead by means of a bail *a'* and a suitable suspension device. (Not shown.)

b and *b'* represent two solenoids arranged end to end within the casing and insulated therefrom by plates *b²* of insulating material. Within the solenoids is an inner tube *b³*, in which the plunger or core *c* reciprocates. The tube *b³* is connected with the casing *a* by iron plates *b⁴*. The plates *b²* and *b⁴* are secured in place by their frictional engagement with the tube *b³* and the casing, but they may be fastened by screws or in any other desirable way. The solenoids are included in a branched electric circuit, one branch of which includes the solenoid *b* and the other the solenoid *b'*, the electrical connections being substantially as shown in my above-mentioned application.

d represents a switch, which is adapted to close the circuit through either branch and break the circuit through the other. The switch is mounted on an arm *d⁴*, pivoted to a suitable support or bearing connected with the casing *a*, the switch co-operating with contact-springs 7 and 8. When the switch is in contact with one of the said springs, it closes the circuit through one solenoid, and when in contact with the other spring it closes the circuit through the other solenoid, the two solenoids being thus alternately energized, as described in my previous application, so that the operator is enabled by oscillating the switch to alternately raise or retract and project the core or plunger *c*, which is movable in the two solenoids.

The driver *e* is connected with the core *c*, and when the latter is projected or depressed the driver is forced into a tack-delivering

throat or nozzle f , affixed to the casing a , and thus caused to drive a tack supplied to said throat, by the means hereinafter described, into the upper and sole of a lasted boot or shoe suitably held for the action of the machine.

I make the coils or helices of the solenoids of aluminium wire, thereby greatly decreasing the weight of the apparatus and enabling it to be much more conveniently manipulated. The iron casing a and the internal iron tube b , connected, as described, with the casing, constitute a holder for the solenoid which increases its effective force and prevents diffusion of the electric current, the casing a by its strength and durability also adding to the usefulness of the machine.

k and k' represent the jaws of the pincers, the same being formed on handles k^2 k^2 , which are pivotally connected at k^3 to a ring or socket k^4 , fitted to rotate in a circular casing m' , affixed to an arm m^2 , which is connected by a pivot m^3 with an arm or bracket m , affixed to the lower end of the casing a . The ring k^4 is adapted to rotate in the casing m' with the pincers, thus permitting the jaws to be oscillated, while the arm m^2 is enabled by its pivotal connection with the bracket m to give the socket m' and the pincers an oscillating motion about said pivot m^3 . The pincers, therefore, while being supported in suitable relation to the tack-delivering throat f , are free to be moved in various directions as required in conforming the upper to different parts of the last, the pincers being used to grasp the upper and draw it to place upon the sole before the tack is driven.

d' represents a switch - operating lever which is pivoted at d^2 to the bracket m and is connected by a rod d^3 to the pivoted arm d^4 , which supports the switch d . The lever d' is arranged in such proximity to the handles of the pincers that it can be manipulated by the same hand that holds the pincers, so that the operator after adjusting the upper can cause the operation of the driver and the insertion of a tack to hold the upper at the point where it was last adjusted.

In Fig. 12 I show a construction of the pincers whereby the outer jaw is moved toward and from the corresponding jaw without moving downwardly to any considerable extent and therefore without a tendency to raise the machine from the work. In this figure the jaws are designated k^5 k^6 , the jaw k^5 being formed on one of the handles k^2 , as in the construction first described, while the jaw k^6 is pivoted at k^7 to the jaw k^5 and connected by a link k^8 with the other handle k^2 , said link and the end of the handle to which it is connected constituting a toggle-joint which imparts a forward and backward movement to the jaw k^6 , the movement being substantially horizontal, with no tendency to raise the machine from the boot or shoe.

i represents a circular tack-reservoir which is mounted to rotate on a stud i' , affixed to

an arm i^2 on the casing a . Said reservoir has curved buckets i^3 , Figs. 2 and 3, on its inner periphery, which elevate the tacks when the reservoir is rotated and drop them into the upper end of the chute j . One side of the reservoir has an opening i^4 , Fig. 2, into which projects an inclined wing or guide j' on the chute j , said guide being arranged to deflect the tacks which fall upon it from the buckets i^3 into the chute. A fixed casing j^2 , attached to the arm i^2 , covers the opening i^4 and guides the tacks that fall over the chute back into the lower portion of the reservoir.

A cam-groove i^5 surrounds the opening i^4 in the tack-reservoir and engages a roll on an arm i^6 , which is affixed to a sleeve i^7 , mounted to oscillate on a stud i^9 , affixed to the casing j^2 . An arm i^{10} is affixed to the sleeve i^7 and is oscillated by the arm i^6 . The arm i^{10} has a spring-pressed foot or extension i^8 , which sweeps over the upper end j^4 of the chute guard or cover j^5 and over a portion of the chute above the guard and agitates or stirs the tacks to prevent them from accumulating in a clogged mass on the chute and insure the proper entrance of a sufficient number of tacks into the chute.

The reservoir i is rotated step by step by means of an arm o , affixed to the pincer-jaw k' , an arm o' , mounted to oscillate on the reservoir-supporting stud i' , said arms being connected by a rod o^4 , and a pawl o^2 , mounted on the arm o' and engaging an internal ratchet o^3 , affixed to the tack-reservoir. Each closing movement of the jaw k' imparts a forward movement to the pawl o^2 and causes a corresponding movement of the reservoir.

The tacks are supplied one at a time to the throat f by an improved let-off mechanism, as follows: A slide r is fitted to move in guides r' r' , Fig. 4, across the throat f and has an oblique opening r^2 , through which the tacks are adapted to pass from the chute to the throat, the latter having an opening with which the opening r^2 coincides when the slide, which moves back and forth across the throat, reaches a given point in its movement. The slide r is provided on its outer side with a rib r^3 or picker r^3 , having one end beveled to form an oblique face r^4 , which is in line with one side of the oblique opening r^2 . The lower end j^6 , Fig. 11, of the chute projects into a slot r^5 in the slide r , said slot being above the rib r^3 , as shown in Fig. 8. The chute has an opening j^7 , Fig. 11, below the end j^6 , for the reception of the said rib. The tacks are therefore delivered by the chute against the outer side of the slide r , as shown in Fig. 6, the lowest tack being in the path of the rib or picker r^3 . When the slide moves, as indicated by the arrow in Fig. 6, the picker engages the lowest tack and deflects it into the oblique opening r^2 , through which it passes into the throat f , as indicated in Fig. 7, the picker arresting the column of tacks in the chute at all times, excepting when it is in the position shown in Fig. 6.

The slide r is moved back and forth across the throat f by the following means: s represents a rod, which is movable in guides s' on the casing a and is bent over at its upper end so as to be within the path of the plunger c , said rod being moved upwardly by the plunger when the latter is completing its upward movement. The lower end of the rod s is connected to one arm of an elbow-lever s^2 , Fig. 4, which is pivoted at s^3 to the bracket or frame at the lower end of the casing. The other arm of the lever s^2 is connected by a rod or link s^4 with the slide r , said rod being curved to enable it to extend across the lower portion of the chute. The rod s is of iron, and is therefore attracted by the core or plunger c , so that when the plunger descends it depresses the rod s . The said rod is therefore reciprocated vertically by the movements of the plunger and reciprocates the slide r horizontally through the lever s^2 and rod s^4 .

When the plunger is elevated by the solenoid b , it raises the rod s and causes the latter to first move the slide r from the position shown in Fig. 6 to that shown in Fig. 7, the picker being thus caused to transfer the lowest tack to the throat, as described.

When the core is depressed by the lower solenoid b' , it depresses the rod s and causes it to move the slide r back to the position shown in Fig. 6, thus removing the rib or picker from the path of the tacks and allowing the column to advance one tack. The operation is thus repeated, a tack being admitted to the throat during each ascent of the driver.

The rod s being of iron and having a much shorter movement than the plunger, reaches the limit of its downward movement and is arrested before the plunger has commenced to drive the tack. Hence the rod, by its adhesion to the plunger resists the downward movement of the latter, so that the plunger is held back until the pull of the solenoid overcomes the magnetic adhesion of the plunger to the rod, the plunger then descending with increased force.

It is obvious that the tack-reservoir may be rotated by a connection with some other moving part of the machine—the rod s , for example.

The tacks may be yieldingly detained in the throat for the action of the driver by jaws $u u'$, mounted on levers $u' u'$, controlled by springs $u^2 u^2$.

The frame which supports the pincer-jaws and throat may be of non-magnetic metal to insulate said jaws and throat from the electric motor, thus enabling the jaws and the tip of the throat to be made of steel for the sake of strength and durability. The same result may be secured by making the frame of iron or steel and insulating it from the motor by a suitable mechanical connection of insulating material.

To facilitate the manipulation of the machine by the operator who has occasion to fre-

quently vary the inclination of the casing a and of the driver, I prefer to support the casing a on two parallel circular tracks $v v$, as shown in Figs. 13, 14, and 15. Said tracks are provided with trunnions $v' v'$, engaged with the supporting-bail, and the casing is provided with rollers v^2 , adapted to run on said track, so that the operator in changing the inclination of the casing does not have to support the weight thereof, the casing being supported by the track in all positions it is required to assume.

I claim—

1. In a tack-driving machine, the combination with two solenoids insulated from each other, a driver operated by the solenoids, and means for delivering tacks to the action of the driver, of an inner tube surrounded by the coils of the solenoids, and projecting at the ends beyond said solenoids, insulated plates secured to the ends of the inner tube and projecting laterally beyond the solenoids, and a metallic casing having its ends connected to said plates and separated thereby from the solenoids.

2. In a tack-driving machine, the combination with a supporting-frame having a tack-delivering throat, a driver movable in said throat, and means for operating the driver, of an arm pivoted to the frame, a socket formed on the arm, and a pair of pincers rotatively engaged with the socket.

3. A pair of pincers comprising an inner jaw having a handle, an outer jaw pivoted to the inner jaw at a point above the grasping portions of the jaws, a link pivoted to the outer jaw, and a handle pivoted to said link and to the handle of the inner jaw.

4. In a tack-driving machine, the combination of a supporting-frame having a tack-delivering throat, a driver, means supported by the frame for operating the driver, a rotary tack-reservoir for delivering tacks to the throat, a pair of pincers connected with the frame, and connections between said reservoir and the pincers, whereby the reservoir is rotated when the pincers are being operated.

5. In a tack-driving machine, the combination of a supporting-frame having a tack-delivering throat, a driver-carrying metallic plunger movable in said frame, electrical means substantially as described for reciprocating said plunger and by which the plunger is temporarily magnetized, a tack-chute communicating with the throat, a tack controlling or feeding slide movable across the throat, and a metallic rod movable on the casing and connected at one end with said slide, its other end being arranged to be attracted to, and operated by the plunger, as set forth.

6. In a tack-driving machine, the combination of a motor, a motor-casing having rollers, a circular track supporting said rollers, and means for supporting said track.

7. In a tack-driving machine, the combination of a supporting-frame provided with a tack-delivering throat, a tack-chute com-

- municating with said throat, a driver and operating mechanism therefor, a rotary tack-reservoir communicating with the tack-chute and provided with a cam-groove, means for 5 rotating said reservoir, a tack-agitator pivoted to a support on the tack-chute, and a connection between said agitator and the cam-groove whereby motion is communicated from the cam-groove to the agitator.
- 10 8. In a tack-driving machine, the combination of a supporting-frame provided with a tack-delivering throat, a tack-chute communicating with said throat, a chute guard or cover having an end j^4 , a driver and operating mechanism therefor, a rotary tack-reservoir communicating with the tack-chute

and provided with a cam-groove, means for rotating said reservoir, and a tack-agitator pivoted to a support on the tack-chute, and having an arm extending into the cam-groove, 20 whereby a positive motion in either direction is imparted to the tack-agitator to sweep it over the end j^4 of the said guard, and the tack-chute.

In testimony whereof I have signed my 25 name to this specification, in the presence of two subscribing witnesses, this 26th day of December, A. D. 1895.

THOMAS C. ROBINSON.
